Primary Examiner — W. A. Teddy Falloway(74) *Attorney, Agent, or Firm* — Elanor Musick; Musick Davison LLP(57) **CLAIM**

The ornamental design for a storage container, as shown.

DESCRIPTION

FIG. 1 is a side perspective view showing my new design for a storage container with a lid attached thereto;

FIG. 2 is a front elevational view of the storage container as shown in FIG. 1;

FIG. 3 is a rear elevational view of the storage container as shown in FIG. 1;

FIG. 4 is a left side elevational view of the storage container as shown in FIG. 1;

FIG. 5 is a right side elevational view of the storage container as shown in FIG. 1;

FIG. 6 is a top plan view of the storage container;

FIG. 7 is a bottom plan view of the storage container;

FIG. 8 is a side perspective view of the storage container with the lid separated; and,

FIG. 9 is an inverted side perspective view of the storage container with the lid separated.

1 Claim, 7 Drawing Sheets# US D887,859 S
